CLAIM

The ornamental design for a telephone, as shown and described.

DESCRIPTION

FIG. 1 is a front elevational view of a first embodiment of a telephone showing our new design;
 FIG. 2 is a left side elevational view thereof;
 FIG. 3 is a right side elevational view thereof; and
 FIG. 4 is a top plan view thereof. Rear elevational and bottom plan views thereof form no part of claimed design.
 FIG. 5 is a front elevational view of a second embodiment of a telephone showing our new design;
 FIG. 6 is a left side elevational view thereof;
 FIG. 7 is a right side elevational thereof; and,
 FIG. 8 is a top plan view thereof.

The rear and bottom of the article, not shown in the drawing, form no part of the claimed design.
